AUTOMATIC STOP FOR DIES

Rudolf Krasberg, Chicago, Ill.

Application August 23, 1947, Serial No. 770,287

3 Claims. (Cl. 164—59)

1

The present invention relates to new and useful improvements in a stop mechanism for feed control devices and more particularly to improvements in an automatic stop mechanism adapted for use with punching, stamping and other types of die mechanisms and to a method of assembling and accurately positioning the stop mechanism with respect to the work to be operated upon.

In general, the invention contemplates the provision of an automatic stop mechanism for a punch press or similar device of the type which includes a reciprocating tool head carrying a punch or other tool which reciprocates in registering openings in a die block and a stripper plate carried thereby. The stripper plate is provided with a channel through which the work, usually a sheet metal strip of varying dimensions, is fed. Such stop mechanisms usually include a pivoted stop lever or rocker arm having at one end thereof an angularly disposed finger or pin which serves as the work engaging stop. Thus, the stop finger is adapted to engage the edge of the work within the previously punched opening therethrough so as to properly position and gauge the work for the succeeding punching operation. Heretofore, each different job necessitated the provision of a special size of stop lever depending upon the type of operation to be performed, the size of the work, and the particular form of die and stripper sets. Thus, one die might require a lever having a longer distance from the pivotal mounting therefor to the stop finger at the end thereof so that an entirely new stop lever would have to be made. Likewise, the stop lever had to be constructed to meet the requirements necessitated by any particular type of stripper plate. Thus, the formation of each new stop mechanism was in effect a tool maker's job requiring a number of hours of specialized work.

With the above in mind, it is one of the principal objects of the present invention to provide an automatic stop assembly having standard size parts which may be assembled in any desired position of adjustment, thus adapting it for different installations and making it possible for a tool room to carry a supply of standard parts so as to obviate the necessity of completely forming a new stop mechanism for each job.

Another object of the invention is to provide an automatic stop assembly which includes a standard size lever arm and a simplified pivotal support therefor, the parts being relatively adjustable during assembly to adapt the assem-

2

bled stop mechanism for a variety of installations.

A further object of the invention is to provide an automatic stop mechanism of the above type which is constructed and arranged so as to be readily applied both above and below the stripper plate and either for left or right hand feeds.

A still further object of the invention is to provide an automatic stop mechanism of the above type wherein the pivotally mounted support for the lever arm is of simplified sheet metal construction and which carries means for securing the lever arm in the predetermined adjusted position thereof.

A still further object of the invention is to provide an automatic stop assembly of the above type wherein the lever arm and the pivotal support therefor have slight permissive sidewise movement in addition to the oscillating pivotal movement to assure proper positioning of the stop finger on the face of the work after each punching or other operation.

The invention still further aims to provide an assembly of the above type which is simple in construction, which can be readily assembled and adjusted, and which includes a minimum number of parts.

The above and other objects of the invention will in part be obvious and will be hereinafter more fully pointed out.

In the accompanying drawing:

Figure 1 is a top plan view showing the stripper plate and stop mechanism;

Figure 2 is a sectional view taken substantially along the line 2—2 of Figure 1 and showing the punch and tappet mechanism;

Figure 3 is a longitudinal section taken substantially along the line 3—3 of Figure 1;

Figure 4 is an enlarged section taken along the line 4—4 of Figure 2 and showing pivotal mounting for the stop lever;

Figure 5 is an enlarged fragmentary perspective view showing the stop lever and the manner in which it is accurately measured and located before final installation;

Figure 6 is an enlarged perspective view of the stop finger and showing the recess therein by means of which it is secured to the pivotal support;

Figure 7 is an enlarged detail sectional view taken substantially along the line 7—7 of Figure 2, and showing the connection between the lever arm and its pivotal support;

Figure 8 is a detail view similar to Figure 1

of a modified stop lever in which a single spring is incorporated to act upon the lever; and

Figure 9 is a sectional view similar to Figure 2 showing the modified form of spring construction of Figure 8.

Referring more in detail to the accompanying drawing, the invention is illustrated in connection with a punch press which includes a bed plate 10 carrying a die block 11. The die block 11 is provided with a vertical aperture 12 into which the punch or other tool reciprocates during operation upon the work. A stripper plate 13 is secured by bolts 14 or the like to the upper face of the die block 11 and is provided with an aperture 15 registering with the die block aperture 12 and through which the punch or other tool reciprocates. In addition to this aperture 15, the stripper plate is provided with another and smaller vertical aperture 16 therethrough which is located in advance of the tool with respect to the line of feed of the work. As illustrated in the drawing, there is a laterally extending open channel 17 in the upper face of the stripper plate 13 and this channel communicates with the vertical aperture 16. As will be herein-after pointed out, the stop lever or rocker arm oscillates within this channel but such channel construction is not essential as the stop mechanism may be mounted on the stripper plate so that only the finger portion thereof extends through the vertical opening 16, if desired.

A punch 18 is carried by a reciprocating tool head 19 to which is secured a spring arm or tapet 20 by means of bolts 21 or the like. The stripper plate 13 is provided with downwardly open recess 23 which forms with the adjacent face of the die block 11 a guide passage through which the work W is fed. Thus, during feeding of the work through this passage, the tool head 19 reciprocates with the punch 18 reciprocating in the aligned apertures 12, 15 in the die block and stripper plate, respectively.

The mounting for the stop mechanism is in the form of a sheet metal bracket 24 having laterally extending ears 25, 25a which are secured by bolts 26 or the like to the side edge of the stripper plate 13, although this bracket may be secured at other locations on the stripper plate as desired and depending upon the operation to be performed. The bracket 24 is provided with forwardly or outwardly extending side portions 27, 27a having the bottom edges thereof joined by a portion 28 so as to provide a U-shaped yoke portion.

The stop lever arm 29 is more particularly illustrated in Figures 5 and 6 and is formed from rectangular bar stock having a body or shank portion 30 and an angularly disposed end portion 31 which forms, in the illustrated embodiment of the invention, a depending stop finger for engaging and positioning the work in a manner to be herein-after more fully pointed out. As shown in Figure 6, the shank or body portion 30 has a recess 32 formed transversely in the upper surface thereof and the location of this recess will depend on the particular details of the operation to be performed.

The pivotal support for the lever arm is formed of sheet metal and is substantially in the form of a bracket 33 having a top portion 34 with 70 depending side portions or wings 35, 35a intermediate the ends thereof. The wings are apertured, as at 36, to receive a pivot pin 37 therethrough. At the ends of the top portion 34 of the bracket or pivotal support 33, the material 75

thereof is continued downwardly and inwardly as at 38, 38a to provide aligned end openings each having a squared cross section corresponding to the cross section of the shank 30 of the stop lever 5 so that it will snugly fit therein. The top portion 34 of the pivotal supporting bracket is cut away to provide two or more spaced openings 39, 39a which are separated by a strap member 40. The strap 40 is adapted to be depressed into the recess 32 in the shank of the lever arm so as to secure the same against endwise movement relative to the pivotal support therefor.

With the lever arm and pivotal support therefor assembled together, the depending side portions 35, 35a of the supporting bracket are fitted within the U-shaped yoke portion between the side portions 27, 27a of the supporting bracket 24 and the pivot pin 37 is suitably mounted in apertures in these side portions 27, 27a. A coil spring 20 42 encircles the pivot pin 37 with one end 42a thereof bearing against the shank or body portion of the lever arm remote from the stop finger 31 and with the opposite end 42b thereof bearing against the bottom portion 28 of the U-shaped 25 yoke portion. The coil spring 42 thus operates, as particularly illustrated in Figure 2, to normally urge the entire stop assembly in a clockwise direction tending to force the stop finger 31 toward or into engagement with the work W 30 being operated upon by the machine.

As shown in Figure 4, there is slight clearance between the apertures 36 in the depending side portions 35, 35a of the pivotal supporting bracket 33 and the pivot pin 37 and similarly there is 35 slight clearance between the side portions 35, 35a of the pivotal supporting bracket and the side walls 27, 27a of the stationary supporting bracket 24. Thus, the assembled pivotal supporting bracket and the lever arm may shift slightly laterally within the yoke portion of the bracket 24. A spring 43 has an angular extension 43a which is secured between the head of the bolt 26 and the laterally extending ear 25 on the bracket 24. The free end 43b of the spring 43 bears against 45 a depending side portion of the pivotal supporting bracket 33 so as to normally resist this lateral shifting or "wobbling" of the assembled pivotal supporting bracket 33 and the lever arm 29. Thus, the spring 43 as viewed in Figure 1, normally urges the lever arm and stop finger 31 in a direction opposite to the direction of feed of the work through the press.

In assembling the pivotal supporting bracket 33 and the lever arm 29 to complete the rocker arm assembly, a standard size of lever arm has its shank portion 30 fitted into the supporting bracket, as shown in Figure 5, and positioned therein with the stop finger 31 in the exact position of adjustment with respect to the work 60 which is to be operated upon and as required in the particular installation. After thus positioning the shank 30 of the lever arm, the top surface thereof immediately adjacent opposite sides of the cross strap 40 on the pivotal supporting bracket 33 is scored by a suitable type of metal scribe S. The lever arm may then be removed from the supporting bracket and the recess 32 is formed therein exactly within the scribed lines by a milling or other suitable operation. Then the lever arm is again fitted into the pivotal supporting bracket therefor with the recess 32 disposed immediately below the strap 40. The strap 40 is then depressed in a suitable manner so that it snugly engages the shank portion of the lever arm within the recess 32, as particularly shown

in Figure 7. Thus, relative sliding movement between the pivotal supporting bracket 33 and the lever arm 29 is prevented and the parts are permanently secured in proper adjusted position for the work to be performed. The portion of the lever arm extending outwardly beyond the pivotal support may be cut off and discarded if desired. It will be readily seen that with this manner of assembling and exactly positioning the stop lever within its pivotal supporting bracket, a supply of more or less standard size stop levers and brackets may be maintained on hand for selection and rapid assembly in the required position of adjustment for any particular installation without the necessity of having a completely new stop mechanism made up for each job.

In operation, the stock or work W is fed through the channel 23 formed between the stripper plate 13 and the die block 11. The tool head 19 descends and carries with it the punch or other tool 18 which passes through the opening 15 in the stripper plate and into engagement with the work. Further downward movement of the punch cuts through the work and enters the die opening 12 so as to thus form the initial punched opening O through the work. Upon the return or ascending stroke of the tool, the work is further advanced and the leading edge of the punched opening comes beneath the stop finger 31 on the lever arm, at which time the coil spring 42 will immediately force the finger downwardly into the punched opening. As the work is further advanced, the trailing edge of the initially punched opening will come into engagement with the adjacent edge of the stop finger 31. By reason of the slight permissive lateral movement of the lever arm relative to the bracket 24, the feeding of the work will force the lever arm in the direction of the feeding movement against the action of the spring 43. The stop finger will ultimately come into engagement with the adjacent side of the vertical opening 16 through the stripper plate so as to positively hold and position the work against further movement. In this position of the work, the tool head again descends and the punch 18 will punch out the next opening in the work and during this downward movement of the tool head, the tappet 20 will engage the top surface of the pivotal supporting bracket 33 and tilt the entire lever arm assembly in a counterclockwise direction, as viewed in Figure 2, so as to elevate the stop finger 31 above the top surface of the work, the opening 16 being of sufficient size to permit this movement. When the stop finger becomes disengaged from the edge of the previously punched opening, the spring 43 operates to immediately shift the lever arm laterally in a direction toward the tool and opposite to the direction of feed of the work so as to positively shift the stop finger out of alignment with the opening and to assure that when the tool head has ascended and the spring 42 again comes into operation for shifting the lever arm in a clockwise direction, the stop finger will be over an unpunched portion of the work and will not descend into the opening from which it was previously removed. This periodic oscillation of the lever arm and its stop finger continues throughout the punching operations.

In Figures 8 and 9 a modified form of spring construction is shown. Instead of using a multiple spring construction for shifting the lever arm as shown in the other views, a single spring 44 is employed. It will be noted that this spring acts on two sides of the lever arm simultaneously

in the same manner that the multiple spring construction previously described acts upon the lever arm. The single spring construction makes for simplicity and economy in design.

From the foregoing description, it will be appreciated that use of the stop mechanism of the present invention will effect a substantial saving of time and expense in various punching, stamping or similar operations by eliminating the necessity of completely making up a new stop lever for each different type of operation to be performed. Thus, by providing a supply of standard size lever arms and pivotal supporting brackets therefor, the parts may be relatively assembled in various positions required over a wide range of shapes and sizes of blanks to be operated upon and various types of stripper plates and other die mechanisms. Therefore, the stop assembly of the present invention is in the nature of a universal stop in that the standard parts may be assembled to operate over a wide range of specifically different installations. True, the cross section of the lever arm may have to be taken into consideration in connection with the operation to be performed and also the size of opening in the stripper plate. However, with a very few different cross sectional sizes, a tool room may be equipped with a supply of lever arms of various cross sections and pivotal supporting brackets therefor and thus obviate the necessity of taking the several hours which normally are required of a tool maker to make up a new stop lever for each different installation or operation. By using the standard parts of the present invention, a new stop mechanism can be formed in a matter of a very few minutes by the location and marking of the lever arm in its supporting bracket as pointed out above. It is obvious that the lever arm may be formed of bar stock of other than square cross section and if from round stock, the engagement of the strap in the recess formed therein would properly lock the parts together.

While one form of the invention has been shown for purposes of illustration, it is to be clearly understood that various changes in the details of construction and arrangement of parts may be made without departing from the scope and spirit of the invention as set forth in the appended claims.

50 I claim:

1. A punch press or the like comprising a die and stripper plate assembly, a reciprocating tool mechanism, a rocker assembly including a sheet metal supporting bracket, means for pivotally supporting said bracket from said die and stripper plate assembly, and an arm secured and carried solely by said supporting bracket and having a transverse recess formed in the surface thereof at a pre-selected position with respect to said bracket, a portion of said bracket extending into said recess for maintaining said arm in the pre-selected position of adjustment, said arm having a stop portion adapted to successively engage and position the work during passage thereof through the die and stripper plate assembly, means carried by the tool mechanism for shifting said rocker assembly in a direction to move said stop portion out of engagement with the work, and spring means for returning said rocker arm with said stop portion in work engaging position.

2. A rocker arm assembly adapted for use as an automatic stop with a wide range of different die sets in punching and similar machines and comprising a supporting bracket having sleeve portions at the ends thereof and depending inter-

mediate side walls adapted to be pivotally connected to the die set, said bracket having a plurality of cut-outs across the top thereof forming at least one strap between said cut-outs and extending substantially transversely of said bracket, and a stop lever snugly fitting within the sleeve portions on said bracket and adapted to be shifted therein to a pre-selected position of adjustment depending upon the requirements of the die set and operation to be performed, and having a recess formed immediately beneath said strap whereby upon depression of said strap into said recess the stop lever and supporting bracket are maintained against relative movement.

3. The method of accurately positioning a substantially standard size stop lever with respect to the work to be operated upon in a punch press or like machine, which method comprises in locating the stop lever in a support in exact adjusted position for the work to be fed through the machine, marking an area of the stop lever through openings in the support, removing the material of the stop lever between the markings

5

to provide a recess, shifting the stop lever to the previous position of adjustment and depressing a portion of the support into said recess for securing the parts against relative movement.
